UNITED STATES PATENT OFFICE.

IRVIN Y. BARINGER, OF PERKASIE, PENNSYLVANIA.

DESIGN FOR A SLEEVE-BUTTON AND CUFF-HOLDER.

SPECIFICATION forming part of Design No. 33,356, dated October 16, 1900.

Application filed September 1, 1900. Serial No. 28,851. Term of patent 7 years.

To all whom it may concern:

Be it known that I, IRVIN Y. BARINGER, a citizen of the United States, residing at Perkasie, in the county of Bucks and State of Pennsylvania, have invented and produced a new and original Design for a Sleeve-Button and Cuff-Holder, of which the following is a specification, reference being had to the accompanying drawings, forming part thereof.

10 The leading feature of my design for a sleeve-button and cuff-holder is a sleeve-button with a cuff-holder secured thereto, formed of a single plate bent back upon itself, the lower portion of which is curved and the upper portion is curved and having its edges extending at an angle thereto.

15 Figure 1 represents a perspective view of a combined sleeve-button and cuff-holder em-

bodying my design. Fig. 2 represents a sectional view on line $x-x$, Fig. 1. Fig. 3 represents a sectional view on line $y-y$, Fig. 1.

In the drawings, A designates a combined sleeve-button and cuff-holder, consisting of a sleeve-button B and of a cuff-holder having the plates C and D, the plate C being curved 25 and the plate D being curved and having its edges E extending at an angle.

Having thus described my invention, what I claim as new, and desire to secure by Letters Patent, is—

The design for a sleeve-button and cuff-holder substantially as shown and described.

IRVIN Y. BARINGER.
